SLICE FOR PAPER MACHINES. BEST AVAILABLE CC

Application filed October 24, 1925. Serial No. 64,565.

This invention relates to a slice for a paper machine and more particularly to a slice adapted for alternately varying at frequently spaced intervals the depth of stock flowing thereunder.

The ordinary paper machine slice consists usually of a metal strip with a straight edge on its lower side. This slice regulates the thickness of the sheet of stock coming onto the wire. When a sheet of paper is formed in the ordinary way with this type of slice, the tendency of the fibers is to run lengthwise with the stream of stock in the machine direction. Because of this fact a sheet of paper is formed which is strong with the machine direction but comparatively weak across the sheet. Furthermore the ordinary slice has only a general vertical adjustment but no local adjustment at frequent intervals along its length. In order to correct the inequality in the strength of the sheet of paper with and across the machine direction, as well as to correct the tendency which the fibers have to settle out in the flow box and behind the slice, various expedients have been tried, including the use of baffles formed of slotted strips or spaced fingers dipping into the stock.

This invention has for one of its objects to accomplish that which the aforementioned expedients have tried unsuccessfully to do and to effect the formation of a sheet of paper having considerably greater strength across the machine direction than hitherto.

It is a further object of this invention to provide locally adjustable means for alternately varying at frequent intervals the depth of stock flowing beneath the slice.

It is a further object of this invention to provide a slice adapted to cause the fibers in the stock flowing beneath the slice to crisscross in their flow and thus to form a stronger sheet of paper of better formation.

It is a further object of this invention to provide a slice having means for varying the height of stock flowing thereunder at frequent intervals along its length and flexible means associated with said slice for levelling the flow of stock and removing the foam and air bubbles formed on the surface thereof.

Other and further important objects of this invention will be apparent from the disclosures in the specification and the accompanying drawings.

This invention (in a preferred form) is

illustrated in the drawings and hereinafter more fully described.

On the drawings:

Figure 1 is a broken front elevational view of a slice embodying the principles of this invention showing a portion of a paper machine;

Figure 2 is a longitudinal section showing a portion of a paper machine with our slice in operation;

Figure 3 is an enlarged section taken on line III—III of Figure 1 showing parts in elevation;

Figure 4 is an enlarged fragmentary section taken on line IV—IV of Figure 1, and

Figure 5 is a perspective view showing the operation of the slice.

As shown on the drawings:

The reference numeral 1 indicates a slice embodying the principles of this invention. Said slice is preferably formed of a sheet of metal of suitable thickness and is provided at its ends with flanged extensions 2. Adjusting screws 3 extend through suitable brackets 4 secured to portions 5 of the paper machine frame and through said flanged extensions 2 to provide means for raising and lowering the slice 1. Said slice 1 is provided along its lower edge with spaced recesses or orifices 6, substantially semi-circular in form. Between each of said recesses 6 there is thus formed a straight edged portion 7.

The slice 1 is shown in Figure 2 in normal spaced position above an apron 8 serving as a dam to hold a predetermined head of stock 9 over the apron 8. The stock—as is well known—flows under the lower edge of the slice onto a travelling, endless wire 10 which passes around a breast roll 11, table rolls 12 and wire rolls 13. As this stock flows over the wire 10 and the table rolls 12, the water is gradually drained through the wire leaving a web of paper formed thereon. In our invention, because of the recessed lower edge of the slice 1, the stock flows under the slice in spaced ridges 14 as shown in Figure 5. A certain amount of the stock also flows under the straight edges 7 in level portions 15. The distance to which the ridges of stock 14 will flow out over the wire will obviously depend upon the speed of the wire and the head of stock behind the slice. With a wire travelling at ordinary speeds, the ridges 14 extend to a considerable distance before flattening out

and during this distance adjacent ridges 14 cross, as at 16, and alternate ridges recross, as at 17. In so doing, the individual fibers are crisscrossed in every direction. Because 5 of the ridges of stock formed, the stock is carried further along the machine, so that said fibers are in a generally crisscrossed position before coming to rest. The pressure of the stock in the ridges 14 also 10 turbes the fibers in the lower level portion 15 causing better weaving of the fibers in the ultimate sheet of paper.

In a paper machine having a slice of usual construction, the flow of stock over the 15 apron and under the slice tends to settle the fibers to the lower side and to permit the fibers to run lengthwise. In our improved slice there is sufficient turbulence set up to prevent the fibers from settling but the turbulence does not result in the formation of 20 an uneven sheet. The currents formed in this flow of stock cause the stock to travel further down the wire before sufficient water is extracted to set the fibers. This is a 25 very desirable feature in paper making.

While the slice as above described operates satisfactorily, we have found that its operation may be further improved by providing means for locally adjusting the 30 height of the recesses or orifices 6 across the length of the slice. Suitable means for this purpose comprise gates 18 slidably secured by means of flanged strips 19 on the back side of the slice. Each gate 18 is here shown 35 as controlling two of the adjacent orifices 6 but it is obvious that wider gates may be used if desired. The gates 18 and the slice 1 are provided at their upper edges with rearwardly extending flanged portions 20 and 21, respectively, through which extend 40 vertical adjusting bolts 22. By means of said bolts 22, each gate 18 may be individually raised or lowered to vary the depth of stock passing through the orifices 6 which 45 said gate controls. The lower edge of each gate 18 is preferably formed with spaced recesses 23 corresponding to the recesses 6 but of lower maximum height. The purpose 50 of the adjustable gates is to vary the depth of stock passing through the orifices 6 and thus to control the thickness of the sheet 55 at all points across its width.

As the stock flows beneath the slice 1, under certain conditions, more or less foam is 55 formed. In order to prevent this foam from carrying along onto the wire and marring the formation of the sheet and also to complete the flattening out of the ridges 14, we have provided a device comprising a 60 flexible strip 24, preferably formed of fabric material and supported transversely of the wire by means of the support or bar 25. Said strip 24 is positioned at a suitable 65 point in front of the slice 1 and is so adjusted vertically that its lower edge 26 just

drags on the surface of the stock. The foam formed on the surface of the stock behind the strip 24 is either dissipated by contact with said strip or else is retained by it and thus prevented from passing along with the 70 stock. The levelling effect of the strip 24 results in the formation of a more uniform sheet of paper but said device is not an essential part of our invention, since the slice 75 will perform very satisfactorily alone.

We are aware that many changes may be made, and numerous details of construction may be varied through a wide range without departing from the principles of this invention, and we therefore do not purpose 80 limiting the patent granted hereon, otherwise than necessitated by the prior art.

We claim as our invention:

1. A slice for paper machines having unobstructed orifices along its lower edge 85 whereby streams of stock of unequal depth are allowed to flow thereunder onto the wire in the direction of said wire.

2. A slice for paper machines having spaced, arc-shaped notches along its lower edge 90 whereby streams of stock of unequal depth are allowed to flow thereunder, and means associated with said slice for separately adjusting the height of groups of 95 said notches.

3. A slice for paper machines having spaced, arc-shaped notches along its lower edge whereby streams of stock of unequal depth are allowed to flow simultaneously 100 thereunder, and means associated with said slice for separately adjusting the height of said notches at frequent points along the length of said slice.

4. In combination with a paper machine, including the apron and wire thereof, a slice 105 associated with said apron to regulate the flow of stock, means on said slice for alternately varying the depth of said flow at frequently spaced intervals along the length of said slice, and flexible means positioned farther along the wire adapted to lie against the surface of said stock.

5. A slice for Fourdrinier paper machines having spaced substantially semicircular orifices along its bottom edge. 115

6. In a Fourdrinier paper machine, the combination with an apron, of a slice having spaced apart notches in its bottom edge, the height of said bottom edge from said apron being such that alternate level and raised streams of stock are caused to flow under said slice in the direction of the wire, the raised streams being allowed to criss cross in their flow on the wire and to flatten out naturally. 120

In testimony whereof we have hereunto 125 subscribed our names.
